UNITED STATES PATENT OFFICE.

JAMES DAVIDSON, OF MONTREAL, QUEBEC, CANADA.

DRAINING RACK FOR CONTAINERS.

Application filed June 25, 1926. Serial No. 118,517.

The invention relates to a draining rack for containers, as described, in the present specification and illustrated in the accompanying drawings that form part of the 5 same.

The invention consists essentially of the novel features of construction pointed out broadly and specifically in the claims for novelty following a description containing 10 an explanation in detail of an acceptable form of the invention.

The objects of the invention are to facilitate the adoption of sanitary measures at farms and other milk stations, and now demanded by city ordinances for the drying 15 out of milk cans under proper conditions; to economize in space and maintain the can in the most effective position until required for use; to support any vessel requiring 20 draining out in a most efficient manner; to eliminate the accumulation of microbes incident to the careless handling of milk cans, previous to being filled; and generally to provide a rack that can readily be attached 25 to the wall and hold the can or other vessel with simple means of fastening.

In the drawings, figure 1 is a side view of the rack, attached to a wall and bearing a milk can.

30 Figure 2 is a front plan view of the rack. Figure 3 is a sectional view of the rack.

Figure 4 is a top view of the rack.

Like numerals of reference indicate corresponding parts in the various figures.

35 Referring to the drawings, the hangers 10 and 11 are here shown in rod form and parallel, having their top ends 12 and 13 in the form of hooks and their bottom ends extending transversely in an outward direction 40 at 14 and 15, and downwardly at 16 and 17, and across to form the bottom bar 18 of a yoke lower end 19 to the said hangers 10 and 11. The sides 16 and 17 of the yoke are dipped centrally at 21, and 22 respectively so that the lower portion of the sides 16 and 17 will more conveniently follow the shoulder of the can.

45 The reinforcing bar 23 is rigidly secured to the hangers 10 and 11, adjacent to the lower end, so that there is no spreading of said hangers.

50 The loop 24 extends from the rear end of the rack and is rigidly secured to the transverse upper sides 14 and 15, of the yoke, and flares a little to give a wide bear-

ing surface to the rear bar 25, and is intended to rest against the wall.

The hooks 12 and 13 in use are secured in the eyes 26 put in the wall and the loop 24 or wall rest maintains the rack quite 60 clear of the wall.

The sliding dog 27 is preferably formed of sheet metal with holes 28 and 29 for the hangers 10 and 11, and the lip 30 projecting downwardly to engage the can 31, and particularly the base rim 32 of said can, after 65 the handle 33 on one side has been slipped in the yoke 19.

The bottom bar 18 of the yoke 19 is curved to meet the contour of the can, and 70 similarly the top sides of the yoke 14 and 15 are bent outwardly to conform to the curve of the bottom bar, so that the can is comfortably held in a bed of approximately 75 the right shape, of course the difference here and there in the size of the can will make no change whatsoever in the use of the invention, and in so far as the construction of the bracket itself is concerned, the mere fastening of the rods and bars in the 80 manner described, is only to give a clear understanding of the use of the invention, as for instance, rods have been mentioned for the construction, whereby it may be of 85 tubular form, in fact a different sort of material altogether may be used, or it may be made in sheet form, the salient feature of the invention being the provision of a bracket that will insure sanitary precautions in the handling of milk cans particularly, 90 though it may be useful in other directions, with changes as to the conditions of use.

What I claim is:—

1. A draining rack for containers comprising a frame having an upper end adapted 95 to be attached to a wall, an intermediate portion extending outwardly from said frame for standing the frame out from the wall, and a lower end formed to support the mouth end of the container, and adjustable 100 means mounted on the frame at the upper portion thereof for engaging the bottom end of the container and holding it thereto.

2. In a draining rack for containers, a frame having a hanger upper portion, a 105 head rest for the inverted container and an outwardly extending member for holding said head clear of the wall, and a fastener for the bottom end of the container extending from said frame.

3. In a draining rack for containers, a frame in skeleton form, having its two upper ends in the form of hooks and its lower end in the form of a recessed yoke, a loop wall rest extending rearwardly therefrom at the upper end of said yoke, and a fastener slidably arranged at said upper end of the rack.
4. In a device of the kind described, a skeleton frame, formed of parallel bars joining a recessed yoke lower end, and having a loop extension from the rear end, and a sliding dog on said parallel bars for engaging an inverted vessel.
5. In a device of the kind described, a pair of parallel hanging bars hooked at the upper end and joining a recessed yoke at the lower end, a reinforcing bar towards the lower end of the hanging bars and a loop forming a wall rest extending rearwardly
- from the yoke, and a sliding dog having an engaging lip adapted to engage the base rim of an inverted vessel.
6. In a device of the kind described, a skeleton frame formed of upwardly extending hanger bars hooked at the top ends to engage eyes in the wall, a recessed lower end in substantially yoke shape to partially embrace the vessel, and to receive the handle thereof, a reinforcing transverse bar to stiffen the hanger bars and a looped wall rest extending rearwardly and forming a wide transverse bearing against the wall, and a sliding dog having a downwardly extending lip adapted to engage the base rim of the vessel.

Signed at Montreal, Canada, this 4th day of June, 1926.

JAMES DAVIDSON.
